(57) **CLAIM**

The ornamental design for a circlip pliers, as shown and described.

DESCRIPTION

FIG. 1 is a perspective view of a circlip pliers in accordance with the present invention;

FIG. 2 is a left side view of the circlip pliers of FIG. 1;

FIG. 3 is a right side view of the circlip pliers of FIG. 1;

FIG. 4 is a bottom view of the circlip pliers of FIG. 1;

FIG. 5 is a top view of the circlip pliers of FIG. 1;

FIG. 6 is a front view of the circlip pliers of FIG. 1;

FIG. 7 is a rear view of the circlip pliers of FIG. 1;

FIG. 8 is a close up perspective view of the circlip pliers taken from FIG. 1; and,

FIG. 9 is a close up left side view of the circlip pliers taken from FIG. 2.

The broken lines shown in the drawings illustrate portions of the circlip pliers that form no part of the claimed design.
